UNITED STATES PATENT OFFICE.

CLARENCE D. PORTERFIELD, OF NEW YORK, N. Y.

RAIL-ANCHOR.

968,797.

Specification of Letters Patent. Patented Aug. 30, 1910.

Application filed July 11, 1908. Serial No. 443,149.

To all whom it may concern:

Be it known that I, CLARENCE D. PORTERFIELD, a citizen of the United States, residing at New Brighton, Staten Island, borough of Richmond, city, county, and State of New York, have invented certain new and useful Improvements in Rail-Anchors, of which the following is a specification.

The invention relates to such improvements; and it consists of the novel construction and combination of parts hereinafter described and subsequently claimed.

Heretofore there have been many inventions seeking the prevention of movement of the rails by means of devices fastened to the rails by bolts, wedges, etc., but these have been found unsatisfactory as the vibration and thrust of the rails, and expansion and contraction caused by variations of temperature, operate to loosen the device on the rails which results in the non-holding of the rails to the ties.

My invention does not depend on bolts or other means independent of the movement of the rails, to effect a practically immovable contact between the device and the rail base, as the tendency of the rails to creep caused by the passage of heavy rolling stock thereupon, forces a tighter wedging between the bottom of the rail and the yoke part of my device thereby wedging the device more tightly on the rail in proportion to the longitudinal movement of the rail which action is automatic and positive and increases the holding power. A downwardly extending flange upon that end of the wedge not engaged between the rail and the yoke, bears against the tie or rail support anchoring the rail to the tie which in turn anchors the rail to the roadbed.

Reference may be had to the accompanying drawings and the letters of reference marked thereon which form a part of the specification.

Similar letters refer to similar parts in the several figures therein.

In the accompanying drawings Figure 1 is a vertical end view showing my invention embracing a rail base shown in cross section. Fig. 2 is a side elevation showing my invention embracing a rail base and resting against the tie or sleeper. Fig. 3 is a plan view of my invention embracing a rail base. Fig. 4 is a plan view of another form of my

invention embracing the rail at an angle of 55 about 30°. Fig. 5 is an isometric view of the wedge part of my invention showing a form of wedge with an elevated shoulder and a foreign substance embedded in the upper surface of the wedge where it comes in contact with the bottom of the rail. Fig. 6 is a vertical end view of another form of my invention in which only one side of the wedge tapers. Fig. 7 shows another form of my invention in which a groove in the under 60 side of the wedge receives a tongue upon the upper side of the bottom of the yoke. Fig. 8 is a side elevation of a part of the rail with my invention as shown in Fig. 7, embracing the rail base. Fig. 9 is a plan 65 view of my invention as shown in Fig. 6. Fig. 10 is a plan view of my invention as shown in Fig. 7. Fig. 11 is another form of my invention in which a tongue upon the wedge engages with a groove in the 70 yoke. Fig. 12 is a side elevation of a part of the rail with my invention as shown in Fig. 11 embracing the rail base. Fig. 13 is a plan view of my invention as shown in Fig. 11. Fig. 14 is another form of my invention as shown in Figs. 11, 12 and 13 with the yoke at an angle of about 30°, to the 75 edge of the rail flange.

My device is superior to other forms using a wedge in that it is simpler of construction, has fewer parts, is easier to apply to the rails and can be made at a much lower cost.

Referring now to the accompanying drawings, R is the rail, W is the wedge, T is the tie, Y is the yoke or clamp, T' is the downwardly extending flange or lug of the wedge which rests against the tie or sleeper.

It will be noticed that I make the yoke or clamp Y in different forms, the upwardly extending ends e e, and the clips c c varying 95 according to the shape of the wedge used and the angle of the yoke when finally adjusted upon the rail. In Figs. 1, 2 and 3 the wedge is shown with two tapering sides, an elevated shoulder on one side of the 100 upper surface and the clips c c of the yoke Y of different lengths. This form is applied to the underside of the rail R from which it is suspended by the clips c c. The wedge W is then placed with its shoulder 105 T' against the tie or sleeper and its opposite end between the yoke Y and the rail R and the yoke Y is driven toward the tie or

sleeper until it engages tightly the bottom, edges, and upper surfaces of the rail flanges between the wedge and the yoke. The yoke Y may be made with sufficient space between the underside of the clips c c and the inside lateral surface of the yoke to apply the yoke to the rail, said inside lateral surface being sloped or inclined as shown best in Fig. 1. The inside vertical surface of the yoke is also sloped or inclined at an acute angle to the edge of the rail flange on one end of the yoke, as shown in Fig. 3. This sloped inside vertical surface engages the sloped side of the wedge and wedges the inside surface of the yoke and the vertical edge of the rail flange; the bottom incline of the wedge engages the bottom of the rail and the inside lateral surface of the yoke, thereby causing practically immovable contact at points 1, 2, 3, 4, 5, 6 and 7. The wedge may be reduced in both lateral and vertical thickness at the free end for the purpose of securing a wedging surface on the upper or under side, and also on the vertical side. As shown in Fig. 5, I have also found it advantageous in some cases to have a shallow depression in the upper surface of the wedge in which can be inserted a different material, such as wood, carborundum, etc., that the base of the rail may be more firmly gripped.

In Figs. 6 and 9 I show a form of my device in which the yoke Y is made with the ends e e having inside bearing surfaces 11 and 13 which contact with the vertical edge of the rail flange, and clips c c with inclined bearing surfaces which contact with the upper sloping surfaces of the rail flange. The clamp is applied from the underside of the rail with the clamp at right angles to the rail. The clamp is then slewed around until the bearing surfaces 11 and 13 are firmly in contact with the edge of the rail flange and when the wedge W is tightly in place between the clamp and the bottom of the rail practically immovable contact is secured. The bearing surfaces 11 and 13 and the edge of the rail flange, may be slightly indented or ribbed or serrated for the purpose of facilitating the gripping.

In Fig. 7 I show another form of the yoke Y in which the tongue or lug —p— projecting upwardly from the upper side of the inside bottom surface of the yoke Y engages in a longitudinal groove in the underside of the bottom surface of the wedge, serving to hold the latter in place during and after adjustment of the yoke.

In Fig. 11 my invention is shown with a tongue or lug o, which projects downwardly from the wedge W and engages with a longitudinal groove in the upper surface of the bottom of the clamp Y for the purpose of holding the wedge in position during and after adjustment. When the wedge and

yoke are in position there is practically immovable contact at the points 16, 17, 18 and 19.

In Figs. 1, 7 and 11 the opening between the edges of the clips c c and between the under surface of the clips c c and the upper side of the bottom of the yoke Y and between the inside vertical edges of the ends e e, is sufficient to permit the application of the yoke to the rail by hooking on first one end of the clamp at an angle that will permit one edge of the rail flange to enter the yoke to a point where the other edge of the rail flange can also enter the yoke.

The form of my device shown in Figs. 4, 80 9 and 14 is applied to the underside of the rail with the rail base at right angles to the lateral length of the yoke. The yoke is then slewed around until the oblique vertical edges of the ends e e are parallel with the 85 edges of the rail flange after which the wedge is introduced between the yoke and the base of the rail and practically immovable contact is secured at 20, 21 and 22.

Having thus described my invention, what I claim as new and desire to secure by Letters Patent is as follows:

1. A device of the character described, comprising a yoke adapted to be adjusted to the rail base at right angles to the axis 95 of said base and then swung so that the base of the yoke is at an acute angle to the axis of said base, and a wedge, bearing at one end against the rail support, and engaging with the opposite end between the under side of 100 the rail base and the upper surface face of the base of the yoke.

2. A device of the character described, comprising a yoke adapted to be adjusted to the rail base at right angles to the axis of 105 said base and then swung so that the base of the yoke is at an acute angle to the axis of said base, and a wedge one end of which engages between the under side of the rail base and the upper surface face of the base 110 of the yoke, with the opposite end bearing against the rail support.

3. A device of the character described, comprising a yoke with upwardly extending ends, the inside vertical surface of one of 115 which is at an angle to the axis of the yoke, and a wedge adapted to engage between the yoke and the under side of the rail base with one end and bear against the rail support with the opposite end.

4. A device of the character described, comprising a yoke with upwardly extending ends, the inside vertical surfaces of which are at an angle to the axis of the yoke, and a wedge adapted to engage between the upper surface face of the base of the yoke and the under side of the rail base with one end, and bear against the rail support with the opposite end.

5. A device of the character described,

comprising a yoke adapted to be adjusted to the rail base at right angles to the axis of said base and then swung so that the base of the yoke is at an acute angle to the axis of said base, and a wedge adapted to engage between the yoke and the rail base, and having an inset comprising a plane surface of

roughened material adapted to increase the friction between the bottom of the rail base and the said plane surface.
